United States Patent Office

Des. 199,833
Patented Dec. 15, 1964

199,833

HAIR DRYER CARRYING CASE OR SIMILAR ARTICLE

William V. Judson, Westport, and Theodore G. Daher, Stratford, Conn., assignors to General Electric Company, a corporation of New York

Filed May 7, 1964, Ser. No. 79,873

Term of patent 14 years

(Cl. D87—5)

Fig. 1.

Fig. 2.

Fig. 3.

Fig. 4.

Fig. 5.

FIG. 1 is a perspective view of a hair dryer carrying case embodying our new design;

FIG. 2 is a front elevational view;

FIG. 3 is a top plan view;

FIG. 4 is a rear elevational view; and

FIG. 5 is an elevational view of the right side thereof with a portion of the handle broken away for convenience of illustration, the left side being substantially similar thereto.

The bottom of the case, not shown, is plain and unornamented.

We claim:

The ornamental design for a hair dryer carrying case or similar article, substantially as shown and described.
